UNITED STATES PATENT OFFICE.

MAURICE DENIS, OF MONS, BELGIUM.

MACHINE FOR PRODUCING THREADS FROM COLLODION AND RECOVERING THE SOLVENTS OF NITRO-CELLULOSE OR CELLULOSE.

No. 834,460.

Specification of Letters Patent.

Patented Oct. 30, 1906.

Application filed March 3, 1905. Serial No. 248,349.

To all whom it may concern:

Be it known that I, MAURICE DENIS, engineer, a citizen of the Republic of France, residing at 2 Rue de la Terre de Prince, Mons, Kingdom of Belgium, have invented certain new and useful Improvements in Machines for Producing Threads from Collodion and Recovering the Solvents of Nitrocellulose or Cellulose; and I do hereby declare the following

10 to be a full, clear, and exact description of the invention, such as will enable others skilled in the art to which it appertains to make and use the same, reference being had to the accompanying drawings, and to letters and figures of reference marked thereon, which form a part of this specification.

15

The present invention relates to the manufacture of collodion filaments or threads, and has for its object means to make such filaments and means for the recovery of the solvents of the cellulose or nitrocellulose, as will be hereinafter particularly described and claimed.

Referring to the drawings, in which like parts are similarly designated, Figure 1 is a view, partly in section and partly in elevation, for making collodion filaments or artificial silk. Fig. 2 is a detail, on a larger scale, of the filament-forming nozzle. Fig. 3 is a plan view of a section on line A A, Fig. 1, where several filaments are united within the apparatus; and Fig. 4, a section on line B B, Fig. 1, where several filaments are united on the exterior of the apparatus and the number of filaments to form a thread can be varied at will.

The solution of collodion, which, as is usual, contains alcohol and ether as solvents, is supplied to the metal tubes 5, that are provided with filament-forming nozzles 6, each of which carries a nut 7, by means of which the length of the nozzle 6, that projects into the down-tubes 9, can be regulated. A stop-cock 20 on each nozzle permits the flow of collodion to be either entirely cut off or be regulated as desired.

A collector 14 contains a suitable liquid at temperature above the boiling-point of the ether solvent desired to be collected—*i. e.*, 36° centigrade for ether—and this liquid for the present explanation may be considered to be water. The collector is here shown as cylindrical and is placed level. The water

flows from the bottom of collector 14 through pipes 12 to the down-tubes 9, which are 55 jointed at 11 to said pipes 12, so as to be moved away from its nozzle 6 into the position *x* and *y*, as indicated. Each pipe 12 has a stop-cock 13, located between the joint 11 and the collector 14, so that the water in any 60 one tube 9 can be cut off independently of the others.

Each down-tube 9 has an opening 8 near its upper end that is provided with an annular flange 8^a, against which flange seats a 65 washer 10. The filament-forming nozzle projects through the opening and washer into the tube 9, the nut 7 abutting against the washer 10 to form a tight joint and said nut regulating the extent to which the nozzle 7^c projects into the tube 9. Those tubes 9 on the left are connected to one or more tubular collecting-chambers 16, of glass, by means of short rubber-tube connecting-section 15, mounted on the neck of the collecting-chambers 16. There may be several of these chambers 16, into which a definite number of tubes 9 discharge, all arranged in horizontal alinement. Each collecting-chamber has a curved discharge-tube 17, terminating in a 80 cup 18, the lower part of which is connected to a metallic collecting-tube 19, which in turn is connected to the circulating-pipe 36. Each of tubes 9 on the right terminates in a cup 18^a, that is connected to a metallic collecting-tube 19^a, that is also connected to the circulating-pipe 36. The circulating-pipe 36 leads to a pump, (indicated at 37), by which the circulating liquid is pumped through pipe 39, which passes through the heater-coil *b* and 9^c into an expansion-tank 38. This tank 38 is connected to the collector 14, that has a pipe 21 leading from its bottom into and near the bottom of a pocket 21^a on the collector. The collector is provided with a gas-outlet valve 95 23, on whose stem 23^a is mounted a float 22, and controls the admission of gas to pipe 24 and condensing-worm 25, whose end enters a vacuum-regulating chamber 26, connected by exhaust-pipe 26^a to a suitable pump 27. 100 A manometer 35 is mounted on chamber 26 to indicate the degree of vacuum, and also connected to the chamber is an automatic mercury circuit-breaker 34, so that when the vacuum, which should be but a few centimeters of water, becomes too great the mercury in

105

one of the arms of the bent tube will leave the terminal and break the circuit of the electric motor 28, that drives the vacuum-pump 27.

On the worm are provided one or more draw-off nozzles 31, each having a tap 30, that is suitably connected to a glass receiver 29 and provided with a valve-controlled air-inlet 32. The vessels 29 are provided with draw-off cocks 33 at their bottoms. The filaments 40 are suitably wound on bobbins, such as 41. The filaments 40 on the left are united within the assembler-tube 16 and emerge from the cups as single threads, while those on the right emerge singly and after passing around suitable guide-pins 43 such number as is desired are wound upon the bobbins 41 in strands.

The operation is as follows: A suitable liquid at a temperature above the boiling-point of ether is introduced into the collector 14, which may be water, and at the commencement of the operation the water fills the collector, and all the cocks on the filament-former being open the water streams down the tubes 9, carrying with it the collodion filaments issuing from nozzles 6. Ether is but very slightly soluble in the water, while the solubility of alcohol at this temperature is about at its maximum. The artificial silk filament will be completely surrounded by hot water as it emerges from the nozzle 6 and be free from contact with air, so that its exterior is not immediately hardened, thereby preventing the imprisonment of solvents in its interior. The ether-vapor rises in the tubes 9 into the collector 14 and aids in forcing the heated water through tubes 9. The descending water carries with it the filament and dissolves the alcohol solvent of the collodion. The internal diameters of the tubes 9 are as small as possible at their lower points between the thread-entrance and exit, so that the liquid in the upper part will be nearly dormant, most of the ether-vapors being liberated at the upper part of the tubes. The ether-vapor accumulating in the upper part of the collector 14 displaces a quantity of water, which passes through the trap 21^a and pipe 21 into the expansion-tank 38. In reality the lowering of the level of the liquid in 14 and its rise in 38 are very gradual. The water drops through the tubes 9 into the collectors 19 and is pumped from them through pipe 36, pump 37, and pipe 39 into the expansion-tank 38 to again pass through the circuit until sufficiently saturated with alcohol to warrant its being distilled or otherwise treated for the recovery of the alcohol. A definite quantity is withdrawn from the circuit and is replaced by a like quantity of unsaturated water. When the water or other liquid in the collector 14 has reached a suitably low level, the float 22 will no longer hold the valve 23 to its seat and the collected ether-vapor will be free to pass by pipe 24 to

the worm 25, that is kept at a sufficiently low temperature to condense the ether-vapor that traverses it, being drawn into the worm by the vacuum-pump 27, the residual gas (air) being drawn through the pump. The ether condensate will drop into the glass vessels 29. By closing tap 31 and slowly opening tap 32 the vacuum in the vessels 29 is broken, and the liquid ether condensate can be drawn off through tap 33, which is then closed, as well as tap 32, and the tap 30 slowly opened again to place the glass vessel in operative connection again with the condenser. As soon as the ether-vapor is drawn off from the collector 14 liquid from the expansion-tank 38 will enter the collector, raise the level therein, and close valve 23. The water circulates in a closed cycle and is maintained at the required temperature by passing through chamber or coil b, located at any desirable point in the circuit. The water may be replaced by a suitable liquid capable of denitrating the filaments formed.

Having thus described my invention, what I claim as new therein, and desire to secure by Letters Patent, is—

1. The combination with a collodion-filament former, of means to maintain the circulation of a suitable liquid past the former and entrain said filament until sufficiently hardened to be reeled, and means to maintain a gas-pressure on the surface of said liquid to augment the hydraulic head, substantially as described.

2. The combination with a collodion-filament former, means to maintain the circulation of a suitable liquid past the former to entrain the filament, and means to collect the vapors given off from the filament, over the liquid-level and means to vent said vapors by a fall of liquid-level, substantially as described.

3. The combination with a collodion-filament former, of a closed circuit containing a suitable liquid in which the filament is formed and entrained, means to collect the vapors liberated from the filament to augment the hydraulic head of said liquid and means to condense said vapors when the hydraulic head exceeds a predetermined pressure, substantially as described.

4. The combination with a collector containing a suitable liquid and a substantially vertical tube connected thereto and having a lateral opening in its upper part, of a nozzle projecting through the opening into the tube to form a filament therein, means to collect the liquid issuing from the bottom of the tube, means to return the liquid into the collector and means to condense the vapors held in the collector, substantially as described.

5. The combination with a collodion-filament former, of means to maintain the circulation of a suitable liquid in a closed cir-

cuit past said former to entrain the filament issuing therefrom and exclude the air, and means at a suitable point in said circuit to maintain the liquid at a suitable temperature, substantially as described.

6. The combination with a collector containing a liquid solvent of one of the solvents of collodion, of filament-forming nozzles, a number of substantially vertical tubes connected to the collector and each having an opening into which a nozzle projects, a joint in each tube to permit it to be swung to and from its nozzle, a collector-tube to collect the liquid passing through said tubes, an expansion-tank connected to the collector, a pump to pump the liquid from the collector-tubes into the expansion-tank, substantially as described.

7. The combination with a collector containing a liquid solvent of one of the solvents of collodion, of filament-forming nozzles, a number of substantially vertical tubes connected to the collector, each having an opening into which a nozzle projects, means to adjust the length that each nozzle projects into its tube, a collector-tube to receive the liquid passing through the aforementioned tubes, an expansion-tank connected to the collector, a pump to pump the liquid from the collector-tubes into the expansion-tank and means controlled by the vapor liberated from the filaments and collected in the collector to liberate said vapor, substantially as described.

8. The combination with a collector containing a liquid solvent of one of the solvents of collodion, of filament-forming nozzles, a number of substantially vertical tubes connected to the collector, one of said nozzles projecting into each, means to permit each tube to be swung to and from its nozzle, a collector-tube to receive the liquid discharged by said tubes, an expansion-tank on the collector, a pump to pump liquid from the collector-tube into the expansion-tank, a con-

denser, means controlled by the vapor liberated from the filaments and collected in the collector to vent said vapor to the condenser, a vacuum-pump to draw the vapor into the condenser and means controlled by the degree of vacuum to automatically control the operation of the pump, substantially as described.

9. In an apparatus such as described, the combination with the collector, of filament-forming nozzles, a number of tubes connected to the collector, one of said nozzles projecting into each tube, a filament-collecting chamber into which a definite number of tubes discharge to unite the filaments into a strand, a collecting-tube into which the chambers discharge and means to return the liquid and vapors to the collector, substantially as described.

10. The combination with a collector containing a solvent of alcohol, of filament-forming nozzles, substantially vertical tubes connected to the collector, one of said nozzles projecting into each tube, a joint to permit each tube to be swung to and from its nozzle, a cock between the joint and collector, a collecting-tube into which said tubes discharge, an expansion-tank connected to the collector, a pump to pump the solvent from the collecting-tubes into the tank, a condenser, a float-controlled valve to vent the ether-vapor into the condenser, a vacuum-pump to draw the vapor into the condenser, an electric motor to drive said pump and means controlled by the degree of vacuum to control the motor, substantially as described.

In testimony that I claim the foregoing as my invention I have signed my name in presence of two subscribing witnesses.

MAURICE DENIS.
